US0D1107444S

(12) **United States Design Patent** (10) **Patent No.:** **US D1,107,444 S**
(45) **Date of Patent:** **** Dec. 30, 2025**

(54) **PASSENGER SEAT**

(71) Applicant: **Textron Aviation Inc.**, Wichita, KS
(US)

(72) Inventors: **Merril Binford Williams**, Wichita, KS
(US); **Frank Joseph Rowe**, Wichita,
KS (US)

(73) Assignee: **Textron Innovations Inc.**, Providence,
RI (US)

(**) Term: **15 Years**

(21) Appl. No.: **29/875,012**

(22) Filed: **Apr. 27, 2023**

(51) **LOC (15) Cl.** **06-01**

(52) **U.S. Cl.**

USPC **D6/356**

(58) **Field of Classification Search**

(57) **CLAIM**

The ornamental design for a passenger seat, as shown and described.

DESCRIPTION

FIG. 1 is a front perspective view showing our new design of a passenger seat;

FIG. 2 is a rear perspective view of the passenger seat of FIG. 1;

FIG. 3 is a front view of the passenger seat of FIG. 1;

FIG. 4 is a rear view of the passenger seat of FIG. 1;

FIG. 5 is a first side view of the passenger seat of FIG. 1;

FIG. 6 is a view of a second side opposite the first side of the passenger seat of FIG. 1; and,

FIG. 7 is a top view of the passenger seat of FIG. 1.

In FIGS. 1-7, broken lines indicate environmental structure that forms no part of the claimed design.

1 Claim, 7 Drawing Sheets
